UNITED STATES PATENT OFFICE

JOHN POUNTNEY UDAL, OF SELLY PARK, BIRMINGHAM, ENGLAND

GUARD FOR PRESSES AND OTHER LIKE MACHINES

Application filed July 15, 1931, Serial No. 550,963, and in Great Britain August 27, 1930.

This invention relates to guards for presses and other like machines, including stamps and hammers, and has for its object to provide improved means for protecting the hands of the operatives against accidental injury.

Guards are already known in which a pair of principal parts are used, one of them being pivoted across the front of the machine so that it can be swung outwards in the direction of the operator, whilst the other is pivoted on the first mentioned part and is likewise arranged to be swung outwards towards the operator. In one form of such guard both parts are caused to swing concurrently in each operation of the press or other machine, and in another form the motion is given first to the second of the above mentioned parts, and after this has been moved to the desired extent, both parts are caused to move together. It is, however, a characteristic feature of such guards that motion is given to both parts in each operative movement of the press or the like.

A disadvantage of these guards is, especially when applied to high speed machines, that owing to inertia effects they are subjected to considerable stresses, and consequently they must to be very well designed and constructed to withstand the forces to which they are subjected. A further disadvantage is that these guards make a considerable movement towards the operator in each stroke, which is inconvenient, and this movement is reduced to a minimum in this guard. Also, as the number of times the hand of the operator is encountered by the guard is very small in comparison with the number of movements given to the guard, the greater part of the work done in moving the guard serves no useful purpose. There is need, therefore, for a guard which, while it performs its main purpose of removing the hand from danger when the necessity arises, and consequently in this condition makes a considerable movement, has normally only a small movement which is little more than sufficient to prevent the hands of the operator from entering the

danger zone after the press has been set in motion.

The invention comprises the combination of a primary guard part pivoted on the machine and controlled by a spring or gravity, 55 a secondary guard part pivoted on the primary part, and means for imparting motion to the secondary part from any convenient moving portion of the machine, the arrangement being such that normally the secondary 60 part only is moved by the machine, the primary part remaining stationary, but in the event of the operator's hand being caught between the two parts of the guard, motion is given to the primary part from the secondary 65 part through the medium of the entrapped hand, for the purpose of carrying the latter out of danger.

In the three accompanying sheets of explanatory drawings:—

Figure 1 is a front elevation and Figure 2 a side elevation showing in the inner position a press guard constructed in accordance with this invention.

Figure 3 is an end view showing the guard 75 in the extended or outer position.

In carrying the invention into effect as shown in Figures 1-3, I secure by means of brackets *z* at the front of the machine on a freely pivoted cross-shaft *a* the upper ends 80 of a pair of depending side arms *b* which are joined by one or more horizontal bars *c*. These form the primary part of the guard. The said part is held in a convenient position across the front of the press or the like under the action of a spring *d* or by gravity, 85 this position being determined by the abutment of an adjustable stop *x* on the shaft *a* against one of the brackets *z*. The primary part of the guard only moves when the necessity arises. Normally it remains at rest. It will be seen from the drawings that one 90 end of the spring bears against the stop *x* while the other end is secured to the bracket *z*.

At a convenient position on the side arms *b* of the primary part of the guard is arranged another cross-shaft *e*, and on this are carried a pair of shorter side arms *f* joined by horizontal members *g* forming the sec- 100

ondary part of the guard. This part normally swings about the axis of the shaft *e*. At the lower part of the arms *f* is provided a horizontal hand striking member *h*, and 5 also a like member *i* is arranged across the lower ends of the arms *b*, the gap between these members *h*, *i*, being such that any obstruction of the thickness of the operator's finger will not allow the secondary part of 10 the guard to pass through the primary part and complete its normal movement. The normal movement of the secondary part of the guard is through the aperture in the primary part which gives the operator access to the tools *j* of the machine. As is 15 usual the moving tool is fixed on the lower end of the vertical slide *k* of the machine and the fixed tool is mounted on the bed *l*.

Motion is given in each operation of the 20 machine to the secondary guard part through any convenient lever or link mechanism connected to the secondary guard part and to any suitable part of the machine such as the crank shaft or plunger. Preferably a crank *m* is attached to one end of the crank shaft *n* or other convenient rotating shaft, and this is connected through a link *o* to a pair of interconnected levers *p*, *q* freely mounted on the cross-shaft *a*. 25 In the example illustrated the lever *p* is attached to an extension of the boss of the lever *q*, the part of the lever *p* which embraces the said extension being split and secured by a screw *y*. The parts *p*, *q* can be 30 adjusted relatively to each other by releasing the screw *y*. Motion is taken from the lever *q* through a link *r* to one of the side arms *f* of the secondary guard part. By mounting the levers *p*, *q* coaxially with the shaft *a* an advantage is obtained in that it allows the whole guard to be conveniently 35 adjusted relatively to the front of the machine. The normal or initial position of the guard is determined as already mentioned by a stop *x*, which is adjustably secured to the shaft *a* and is arranged to abut against one of the brackets *z*. When it is required to cause the initial position of the guard to be nearer or further from the machine than is shown in the drawings the 40 stop *x* is suitably adjusted.

In each action of the machine the secondary guard part is caused to swing relatively to the primary part (which remains stationary) for the purpose of closing the aperture in the primary part and so preventing access of the operator's hand to the tools during the active stroke of the machine. This action is illustrated by the full and dotted 45 lines in Figure 2. Normally no movement is given to the primary part of the guard and the secondary part moves between the position indicated by the full and dotted lines. Should the operator's hand be in the way it 50 is caught between the lower horizontal mem-

bers *h*, *i*, of the primary and secondary guard parts. As the hand thus prevents further relative movement of the said parts, both parts move together against the action of the controlling spring *d* or weight, and the hand is carried away from the dangerous position as shown in Figure 3. For normal purposes the movement of the secondary guard part can be a comparatively small one, but when the hand is trapped a large 70 movement of the two guard parts is desirable, and the various members of the mechanism are advantageously proportioned and arranged in any convenient manner such as that illustrated to satisfy this requirement. 75 An important feature of the design of the guard is the disposition of lever *q* and link *r* relative to each other and lever *f*. The arrangement is such that in the early part of 80 the stroke of the guard the first small angular movement of the lever *q* causes a relatively larger angular movement of the lever *f*, whereas later in the stroke the angular movement of the lever *q* is very much larger than that of the lever *f*, which at the end of 85 the stroke is hardly moved at all. This result is obtained because the upper lever *q* and its link *r* form a toggle, and the angle between is at the maximum at or near the end of the guard movement. 90

It will be apparent from the foregoing that in guards constructed in accordance with my invention only the smaller or secondary part of the guard is normally moved in each action of the machine, and the amount of movement given to this part is then little more than sufficient to prevent the hand from entering the danger zone while the machine is in motion. In the event, however, of the hand being in the dangerous position when the machine is started, the hand itself serves to interconnect the guard parts and so cause an ample movement to be given to the main guard part for carrying the hand clear from danger. The larger part of the guard, therefore, only comes into action when the necessity arises. The hand is also pulled out for the same reason if caught between the secondary part of the guard and the lower die of the tool of the press. As soon as the secondary part encounters an obstruction of any kind both guard parts move together and risk of trapping the hand between the secondary part of the guard and a fixed part of the machine is thereby obviated. 105

The invention is not limited to the example above described, and subordinate details can be varied to suit different requirements. 110 I desire to emphasize, however, that the mechanism shown in the accompanying drawings is to be preferred as it enables the required motions of the guard parts to be readily obtained in a manner which is con- 115

veniently applicable to many different forms of existing machines.

Having thus described my invention what I claim as new and desire to secure by Letters Patent is:—

In press and like machine guards, the combination of a primary guard part, a cross shaft carrying the upper end of the said part, controlling means acting on said 10 part, a secondary guard part pivoted on the primary part, a source of motion, and actuating means for transmitting movement to the secondary part from the source of motion, said means comprising a pair of relatively 15 adjustable interconnected levers mounted coaxially with the cross shaft, a link connecting one of the levers to the source of motion, and a link connecting the other lever directly to the secondary part intermediate 20 its upper and lower ends, the latter lever and link forming a toggle for imparting a large angular movement to the primary part in the event of the operator's hand being caught between the two parts of the guard, 25 substantially as described.

In testimony whereof I have signed my name to this specification.

JOHN POUNTNEY UDAL.
